LOCK

Alonzo J. Gilbert and William E. Gilbert,
Toledo, Ohio

Application June 3, 1936, Serial No. 83,341

10 Claims. (Cl. 292—141)

This invention relates to locks.

This invention has utility when incorporated in a structure having a plurality of closures wherein a lock may operate to lock one of the closures and be in turn rendered inaccessible by the position of another of the closures.

Referring to the drawing:

Fig. 1 is a fragmentary side view of a motor vehicle embodying the invention herein;

10 Fig. 2 is a partial view on the line II—II, Fig. 1;

Fig. 3 is a view similar to Fig. 2 with the parts in unlocking position and exposed by removal of the cover plate;

15 Fig. 4 is a view similar to Fig. 3 with the parts in locking position;

Fig. 5 is a view on the line V—V, Fig. 2;

Fig. 6 is a view on the line VI—VI, Fig. 4; and

20 Fig. 7 is a fragmentary view, similar to Fig. 3, disclosing a modified construction, more particularly adapted to locks herein of smaller dimensions.

Motor vehicle 1 of the sedan or multiple door type of closed automobile has laterally adjacent openings or doorways 2, 3, spaced by frame member 4, opposite sides of which provide jambs 5, 6, one at each opening. Doors 7, 8, serve as closure members for the openings 2, 3, respectively, and are normally operated from the exterior of the vehicle by handles 9, and from the interior by handles 10. The handles 10 may not only serve as opening means but, by swinging in the opposite direction, may lock the doors against opening by means of the handles 9.

It is desirable that, under certain conditions, 35 the door 2 be temporarily rendered inoperable, as for example when small children are riding on the rear seat of the vehicle and may seek to operate the handle 10. In other instances, passengers may mistake the door operating mechanism for the window operating mechanism while the vehicle is in motion. The lock herein disclosed, may prevent the rear door from being opened until the front door has been opened and then only at the will of the driver or 40 another who may be in control to release the lock for the rear door.

50 Mounted on jamb 6 by means of screws or bolts 11 is plate 12 having opposing overhang portions 13, 14, inwardly extending thereover to provide a way 15. Reciprocably along the way 15 is slide 16 having extension 17 therefrom providing operating means therefor as well as movement limiting means determined by the length of clearway region 18 in the overhang 14.

Angularly extending from the plate 12 is tubu-

lar guide 19 having tapered portion 20 from the plate 12 to constant diameter portion 21 terminating at the face of the jamb 5. The guide 19 carries reciprocable bolt 22 having by pin 23 connected therewith flexible link 24 extending to slide 16. A suitable connection with the slide 16 is provided by loop 25 in the link 24 through opening 26 and fixed by solder 27. This is an effective thrusting means for the linkage in the way 15 without crimping of the flexible link 24. 5 By shifting the slide 16, the bolt 22 may be shifted into and out of opening 28 in the door 2 thereby providing the reserve supplemental locking means therefor.

Cover plate 29 may have snap assembly with the plate 12 and not only protect the parts but serve as auxiliary link guide means. The plate 12, slide 16, and cover 29 are all thin sheet metal stampings assembled into a flat unit having an overall thickness less than the normal clearance 20 between the jamb and door of a motor vehicle so that after installation, which is quickly and easily accomplished, the door 2 may not only be locked but the door 3 closed, thereby rendering the extension 17 inaccessible and requiring an 25 opening of the door 3 before this reserve lock may be operated.

While the lock of the disclosure has special utility in motor vehicles, it may be effective between different openings of one or more structures or even as a lock for a closure whether or not the operating means may be protected or 30 remotely placed.

The parts being of thin materials are singly 35 flexible and the slide 16 is readily assembled in the way 15 even though it is of greater length than the clearway 18 for the slide 16 has reduced width terminus 30 and by a slight flexing may be placed in operative relationship with the overhangs 13, 14, (Fig. 3).

In the construction of locks embodying features of the invention herein, especially when of smaller dimension, the slide 16 may have a bifurcated terminus providing slide extensions 31, thereby providing stability for the slide in its 40 action with overhangs 14, 15; the loop 25 having connection therewith adjacent the central portion of the slide.

In lieu of the extension 17 and the clearway 45 18, operation of the lock may be controlled by extension or pin 32 from the slide 16 extending through slot 33 in the face of the cover 29.

What is claimed and it is desired to secure by United States Letters Patent is:—

1. For a structure having a pair of laterally

5 adjacent openings with a spacing member there-between, a first and second closure respectively for the openings, the combination of a lock in the spacing member for the first closure, and operating means therefor mounted on a side of the spacing member and rendered inaccessible by and actuatable independently of the second closure.

2. A lock comprising a bolt, a guide for the bolt, a slide, a way for the slide angularly disposed to the guide, and a flexible link between said slide and bolt.

3. For a structure having a pair of laterally adjacent openings, a member therebetween providing a pair of parallel jambs, a first and second closure for said openings, the combination of a bolt shiftable to and from one of said jambs for locking the first closure, a slide shiftable along the other jamb, and linkage between said bolt and slide.

20 and slide.
21 4. For a structure having a pair of laterally
22 adjacent openings, a member therebetween pro-
23 viding a pair of parallel jambs, a first and second
24 closure for said openings, the combination of a
25 bolt shiftable to and from one of said jambs for
locking the first closure, a slide reciprocably
shiftable along the other jamb, and a flexible link
between said bolt and slide.

between said bolt and slide.

5. For a structure having a pair of laterally adjacent openings, a member therebetween providing a pair of parallel jambs, a first and second closure for said openings, the combination of a bolt shiftable to and from one of said jambs for locking the first closure, a slide reciprocably shiftable along the other jamb, and a flexible link between said bolt and slide, said slide rendered inaccessible upon closing the second closure.

6. A lock including a frame providing a way and a guide angularly extending therefrom, a

slide in said way, a bolt in said guide, and a flexible link therebetween.

7. A lock for a closure comprising a plate providing a way, a tubular member extending angularly from said way, a slide shiftable in said way, a bolt shiftable in said extension, and flexible linkage therebetween.

8. In a lock, a plate having oppositely disposed overhangs providing a way, a slide in said way having an operating extension, a cut-out region in one of said overhangs limiting shifting of the slide, said slide being of greater length than the cut-out region, and a reduced width terminus for said slide for facilitating assembly with the way. 10 15

9. In a lock, a plate having oppositely disposed overhangs providing a way, a slide in said way having an operating extension, a cut-out region in one of said overhangs limiting shifting of the slide, a bolt, linkage between said bolt and slide, and a cover plate for the slide and way having snap assembly with the plate, said cover and plate cooperating to confine movement of the linkage to said way.

10. For a structure including a pair of laterally 25 adjacent openings spaced by a member providing a pair of parallel jambs, one for each opening, a first and second closure respectively for said openings, the combination of a lock for the first closure comprising a plate providing a way mounted on the jamb of the other closure, an extension therefrom providing a guide to the jamb of the first closure, a bolt in said guide, a slide in said way, a flexible link between said slide and bolt, the bolt locking the first closure and the second closure being positionable to render the slide inaccessible.
